UNITED STATES PATENT OFFICE

VICTOR W. GIDEON, OF CHICAGO, ILLINOIS, ASSIGNOR TO WILSON JONES COMPANY, A CORPORATION OF MASSACHUSETTS

POSTING TRAY

Application filed December 14, 1927. Serial No. 239,882.

This invention relates to a posting tray of that type involving a drop side whereby the sheets may be offset, and it is an object of this invention, in connection with this type of tray, to provide an improved form of follower which can be easily and quickly operated, and with an improved form of drop board for limiting offset movement of the sheets. The posting tray also embodies other novel features of construction which will be pointed out as the description proceeds.

This invention comprises the novel structure and combination of parts hereinafter described and more particularly pointed out and defined in the appended claims.

In the accompanying drawings, which illustrate a preferred embodiment of this invention and in which similar reference numerals refer to similar features in the different views:

Figure 1 is an end elevational view of a posting tray involving this invention.

Figure 2 is a side elevational view of the posting tray.

Figure 3 is an enlarged sectional view taken upon line III—III of Figure 2 with the drop side in its lowered position to illustrate the manner of offsetting the sheets.

Figure 4 is a top plan view of the tray.

Figure 5 is an enlarged sectional view taken on the line V—V of Figure 4.

Figure 6 is an enlarged fragmentary interior elevational view of the locking means for the drop side.

Figure 7 is an enlarged sectional view taken substantially upon the line VII—VII of Figure 4.

Figure 8 is an enlarged sectional view taken substantially upon the line VIII—VIII of Figure 7.

Figure 9 is an enlarged sectional view taken substantially upon the line IX—IX of Figure 7.

Figure 10 is an enlarged sectional view taken on the line X—X of Figure 6.

The posting tray involving this invention is in the form of a metal box comprising the ends 1 which are provided with suitable handles 2 whereby the tray may be easily carried and handled. The tray box has a rigid

side 3 and drop side 4. The sides and ends of the box-like structure are adapted to be secured or welded to suitable corner posts 5 which are formed of sheet-metal in the manner shown in Figure 10.

The base of the tray is formed by a pair of longitudinally extending channel members 6 which may be covered with some soft material or fabric in order to avoid the scratching of the furniture when the tray is in use. These channel members have bolts 7 welded to the interior of the webs. With reference to Figure 5, it will be noted that these bolts 7 have long flat feet, and these feet are welded to the webs of the channel members. Upon the lower interior margin of each side of the box there is welded an angle member 8 (Figure 8). That portion of the bottom of the tray which forms the sheet support consists of suitable plate members 9, 9 which are superposed over the top flanges of the angles 8, and the bolts 7 of the channel members extend through the top flange of the angle members 8 and the plates 9 as shown in Figure 8. The inner edges of the plates 9 are sufficiently spaced apart to provide a suitable passage for the follower. A runway 10 for the follower is provided below the said passage. It will be noted that this runway 10 consists of a sheet-metal casing having upwardly directed sides terminating in attaching flanges 11 which are secured to the bottom of the plates 9 by welding or the like. In addition, suitable clips 14 on the bottom of the plates 9, as shown in Figure 3, may extend under the attaching flanges. It will be noted that the sides of the runway are spaced apart a greater distance than the passage between the plates 9 whereby the plates 9 form ledges overhanging the longitudinal margins of the runway 10 for a purpose that will later appear.

In the bottom of the runway, there is a suitable rack 13 which is provided with two rows of ratchet teeth 13a which slope in the direction of the operative movement of the follower.

At one end of the tray, a pair of lugs 14 integral with clips 14a (Figure 7) extend from the plates 9, only one of which is shown. A swinging leaf 15 is hinged to the lugs 14 by 100

means of a suitable rod 16. At the same end of the tray, there is an inwardly extending ledge 17 at the top thereof, and the swinging leaf 15 is connected to the ledge 17 by means of a pair of toggle plates 18. These 5 toggle plates are hinged at their adjacent ends, as indicated at 19, and the outer ends thereof are respectively hinged to the swinging plate 15 and the ledge 17, as indicated at 10 20 and 21.

15 A coil spring 22 surrounds a hinge pintle 20 and its ends bear against the plate 15 and the adjacent toggle plate 18. The lower outer toggle plate 18 is provided with a pair of finger pieces 23 for effecting manual 20 operation of the toggle plates. It is, therefore, evident that in changing the plate 15 from one position to the other, for example, from its upright position to its inclined position, the toggle must be initially operated by hand. When, however, the toggle plates are moved to a predetermined position, the spring 22 will come into action and snap the plate to its inclined position. Obviously, the 25 same action will take place in moving the plate 15 from its inclined position to its vertical position. The downward flexing movement of the toggle plates is prevented by a pair of plates 24 (Figure 4) which are attached to the outer toggle plate and overlap the inner toggle plate. These overlapping limiting plates 24 carry the aforementioned finger pieces 23.

30 A movable follower cooperates with the plate 15 for holding sheets therebetween. 35 This follower consists of a pair of rails 25 (Figure 8) which extend beneath the ledges formed by plates 9 and which are supported at both ends by suitable rollers 26 which 40 travel upon the runway 10 beneath the ledges. At one end of the rails 25 are upwardly extending flanges 27, best shown in Figure 8, to which the sides 28 of a sheet-metal support 29 are attached. This sheet-metal support 45 has a straight back 30 and the front edges of the sides thereof slope rearwardly and upwardly and have an inclined plate 31 attached thereto. Upon the bottom edge of the inclined plate 31 there is hinged a compression plate 32, and this compression plate is connected to the upper end of the inclined plate 31 by means of a pair of toggle plates 33 and 34 in a manner similar to the first 50 described toggle plates in connection with the compression plate 15. A plate 35 is secured to the toggle plate 34 and overlaps the toggle plate 33. This plate 35 is provided with finger-pieces 36 for operating the toggle plates.

55 Housed within the sheet-metal support 29 there is a sliding detent 37 which is in the form of a plate having its lower end bifurcated as shown in Figure 8, and having 60 its end edges engaging the rack teeth 13^a.

From the bifurcation of said detent, there extends a stop lug 38 which projects through a bifurcation in the back of the support 29. This sliding detent is connected by a spring 39 within the hollow sheet-metal support 29 70 to the plate 31. This spring is normally effective for yieldingly maintaining the detent plate in engagement with the rack teeth but is of a sufficiently yieldable nature to allow the detent to readily move over the 75 rack teeth when the follower moves forward for compression purposes. The detent is adapted to be actuated by a handle 40 which is attached to the detent plate, as indicated at 41. Above the detent plate 37 the handle 80 40 is outwardly offset as shown in Figures 7 and 8, and overlaps the rear wall of the hollow support 29, as indicated by dotted lines in Figure 8. It might be mentioned that the upper portion of the wall of the 85 hollow support 29 is bifurcated as indicated at 43 in order to allow the operating handle for the detent to be outwardly offset.

The drop side 4 of the tray carries a spring-impelled latch 44 (Figure 6) which is adapted for entering a notch 45 (Figure 10) in one of the corner posts of the tray. The operating end of this latch is bent at an angle and connected to an operating lever 46 which is pivoted in an enlargement 47 upon the 90 outer side of the drop side, as shown in Figure 2. The lever 46 is pivoted intermediate its ends as indicated at 48, and a second latch member 49 is connected to the lever at a point diametrically opposite to the connection of the latch 44. The construction is such that when the outer end of the lever 46 is elevated the latches will be withdrawn from the locking recesses in the corners of the posts.

95 The aforementioned drop side 4 is provided with a swingable abutment 50 which is hinged at a suitable point intermediate the top and bottom of the side, as shown in Figures 3 and 8. This swingable abutment 50 is adapted to lie flat against the interior of the drop side when the drop side is in vertical position. It might be mentioned that the drop side 4 has an angular member 51 (Figures 4 and 5) adjacent each end. The lower end of member 51 has a projection 52 adapted to extend into an aperture 54 in the adjacent plate 9 when the drop side is in vertical position. This projection 52 is provided with a lateral hook-shaped offset 53, with the result that when the drop side is swung downwardly, the offset portion 53 will engage the sides of the posts 5 and support the drop side in horizontal position. To one member 51 there is secured a resilient leaf-spring 55 (Figure 5) and the swingable abutment 50 is provided with a foot piece 56 which has one edge in frictional engagement with the leaf-spring 55. When the abutment 50 is swung into vertical position with respect to its side, as shown in Figure 8, the foot piece 56 will 100 105 110 115 120 125 130 135 140

engage the drop side for stopping the swing of the abutment 50 at its vertical position, as shown in dotted lines in Figure 8. The spring 55 exercises sufficient pressure on the foot 5 piece to maintain the swingable abutment 50 in either its operative or inoperative position.

In the use of this tray for posting purposes, it may be desirable to offset certain sheets. In such a case, the lever 46 is operated to unlatch the drop side which may then be swung outwardly until the hook-shaped projections 53 engage the inner sides of the posts 5 and support the drop side in horizontal position. The swingable abutment 50, which is in the form of a plate hinged to the inner side of the drop plate, may then be swung to the position shown in Figure 3, in which position it is supported against outward movement by the aforementioned foot piece 56 which rests against the drop side. With the tray in this position, the sheets may be offset against the stop plate or abutment 50 as shown in Figure 3. When the posting operation is completed and the sheets are again returned to the body portion of the tray, it may be desirable to compress the same. In such event it is only necessary to push the follower forwardly, the detent riding easily over the ratchet teeth. It might be mentioned that when it is desired to unclamp the sheets between the two compression members, it will be necessary to elevate the locking detent so that the follower can be slid in the opposite direction to the fixed compression member.

It will be appreciated that on account of the rollers that support the follower and the ease with which the detent will ride over the ratchet teeth when the follower is moved toward compressive position very little difficulty will arise in moving the follower to compressive position. The operation can be very easily and quickly performed and is a vast improvement over followers heretofore used. It will also be appreciated that in providing a limiting stop upon the inner side of the drop side, which limiting stop is swung downwardly alongside of the drop side when the same is in vertical position and which may be moved at right-angles when the drop side is in its horizontal position, a novel and more efficient device is obtained than other devices of this character.

I am aware that many changes may be made, and numerous details of construction may be varied through a wide range without departing from the principles of this invention, and I therefore do not purpose limiting the patent granted hereon, otherwise than as necessitated by the prior art.

I claim as my invention:

1. In a posting tray having a runway with ledges projecting over said runway, a follower comprising rails in said runway and having rollers engaging beneath said ledges,

and cooperating latching members between said follower and runway, said members easily sliding over each other when said follower is moved toward compressing position and automatically locking when said follower is moved to its operative position.

2. A posting tray having a runway in the bottom thereof with ledges extending over said runway, in combination with a follower having members in said runway and having rollers engaging beneath said ledges for the purpose set forth.

3. In a posting tray having a runway with ledges extending over the margins of said runway, a follower comprising a pair of rails in said runway, rollers carried by said rails engaging beneath said ledges, a ratchet bar in said runway, said follower embodying an upright member, and a slidable detent carried by said member for engaging said ratchet bar.

4. In a posting tray, a compression member hinged at its lower end and swingable from an inclined to a substantially vertical position, a rest for supporting said compression plate in inclined position, a pair of toggle plates connecting said rest and compression plate, and means for manually flexing said toggle plates.

5. In a posting tray, a follower comprising a rolling base and an upright support embodying an inclined rest, a compression plate hinged to the bottom of said rest, a pair of toggle plates connecting the upper portion of said rest with said compression plate, and means for manually flexing said toggle plates.

6. In a posting tray comprising a box having a body portion with a runway extending longitudinally thereof, a pair of ledges overhanging the lateral margins of said runway, a follower having roller supports located in said runway beneath said overhanging ledges, and cooperating members between said follower and runway for locking said follower against movement in one direction.

7. A posting tray having a runway in the bottom thereof with ledges extending over said runway, in combination with a follower having rollers travelling upon the bottom of said runway beneath said ledges, a detent carried by the follower and means below the upper surface of said ledges adapted for cooperating with said detent for latching the follower in adjusted position.

8. A posting tray having a bottom with a substantially central longitudinally extending runway, ledges on the bottom of the tray overhanging the runway, in combination with a follower having rollers traveling on the bottom of the runway and located beneath said overhanging ledges.

9. A tray having a bottom composed of spaced members and a runway beneath said spaced members and spanning the space therebetween, said spaced members over-

hanging portions of said runway in combination with a follower having rollers in said runway and located beneath said overhanging portions and adapted for travelling upon the bottom of said runway.

5 10. In a posting tray, a bottom composed of spaced members, a runway member beneath said spaced members and spanning the space therebetween, said spaced members over-
10 hanging portions of said runway member, a follower in said tray having side rollers adapted for travelling upon said runway member beneath said overhanging portions, a detent carried by said follower, and means
15 on one of said members for cooperating with said detent for latching said follower in adjusted position.

In testimony whereof I have hereunto subscribed my name.

VICTOR W. GIDEON.
